UNITED STATES PATENT OFFICE

110,758

DESIGN FOR A COAT

Jack Steinberg, New York, N. Y.

Application July 6, 1938, Serial No. 78,287

Term of patent 3½ years

To all whom it may concern:

Be it known that I, Jack Steinberg, a citizen of the United States and a resident of the city of New York, in the county of New York and State of New York, whose post office address is 545 West End Avenue, city and State of New York, have invented a new, original, and ornamental Design for a Coat, of which the following is a specification, reference being had to the accompanying drawing, constituting a part thereof.

Fig. 1 is a front view of a coat in closed position showing my design.

Fig. 2 is a rear view thereof.

Fig. 3 is a front view of the coat shown in Fig. 1 in open position.

Fig. 4 is a rear view of Fig. 3.

I claim:

The ornamental design for a coat, substantially as shown.

JACK STEINBERG.
